UNITED STATES PATENT OFFICE.

JOHN A. RHOADES, OF OSHKOSH, NEBRASKA.

CROSSING SIGNAL.

Application filed December 22, 1925. Serial No. 77,150.

The present invention relates to improvements in crossing signals and has for its principal object to provide a warning signal which is adapted to be placed at the intersection of 5 the highway with the railroad tracks, as well as being adapted for use at the corners of street intersections.

One of the important objects of the present invention is to provide a signal which includes 10 a slidable and rotatable signal arm, the same being supported on a suitable standard in such a manner as to be readily and easily visible by vehicles and pedestrians approaching the intersection.

15 A further object is to provide a crossing signal wherein the signal members are arranged in pairs and are further adapted for simultaneous operation in order to facilitate the regulation of traffic at the point of intersection.

20 A still further object is to provide a crossing signal of the above mentioned character which will at all times be positive and efficient in its operation, the same being further simple 25 in construction, inexpensive, strong and durable and further well adapted for the purpose to which it is designed.

Other objects and advantages will become 30 apparent during the course of the following description taken in connection with the following drawings.

In the accompanying drawings, forming a 35 part of this application, and in which like numerals designate like parts throughout the several views:

Figure 1 is a diagrammatical view of a street intersection showing the arrangement of my improved signalling means at the corners thereof.

40 Figure 2 is a side elevation of one of the signal members, partly shown in section, and illustrating the means for effecting the actuation of the signal member.

Figure 3 is a sectional view taken approxi- 45 mately on line 3-3 of Figure 2, looking in the direction of the arrows.

Figure 4 is a similar section taken on line 4-4 of Figure 2.

Figure 5 is a fragmentary sectional view 50 taken on line 5-5 of Figure 4, and

Figure 6 is a view similar to Figure 1 showing the signalling device as associated with a railroad crossing.

In the drawings wherein for the purpose of 55 illustration is shown the preferred embodi-

ment of my invention, the numerals 1 and 2 designate generally one pair of cooperating signalling members, the other pair of cooperating signals being indicated by the numerals 3 and 4 respectively, the signals 1 and 2 are 60 preferably arranged at diagonally opposed corners of a street intersection designated generally by the letter A, while the other pair of signal members are arranged at the other diagonally disposed corners. The signals 1 65 and 2 are adapted to regulate the traffic which may be traveling either north or south, while the other pair of signals are provided for regulating the traffic which travels east and west.

Each of the signal devices comprises a platform 5 which is adapted to be supported on the upper end of any suitable support designated generally by the numeral 6. The support may comprise the usual electric light support provided at each corner of the street intersection A. It is of course to be understood that the support is of such height as to enable the signal device to be disposed sufficiently above the surface of the ground so as 70 not to interfere with the vehicles traveling over the highways when the signal is disposed in an operative position. A pintle 7 extends upwardly from the platform. Adapted to be supported on the pintle, and further adapted 75 for rotation thereon is what I term as a guide block 8. The purpose of this block will hereinafter be more fully described. Also adapted to be disposed on the pintle 7 between the bottom of the block and the upper face of the 80 platform 5 is a spacing collar 9, the purpose of 85 which will also be presently apparent.

The signalling arm includes a base 10, the same being provided at its intermediate side portion with the lateral projection 11. End 90 walls 12 extend upwardly from the base 10 adjacent the respective ends of the base. Longitudinally extending bars 13 and 14 are secured at their opposite ends to the respective side edges of the end members 12, and as is 95 clearly shown in Figure 2, these bars are arranged in parallel spaced relation, and provide tracks. A metallic sheathing 15 extends around the sides and ends of the signalling arm as clearly shown in Figures 2 and 3.

The base 10 of each signalling arm is provided with a central longitudinally extending slot 16 and provides a means whereby the pintle 7 and the block 8 supported on the same 100 may be disposed upwardly through the base of 110

the signalling arm, and permit the block to be disposed between the opposed bars 13 and 14. Suitable rollers 17 are mounted on the opposite sides of the block 8 and cooperate with the bars 13 and 14, as well as with the base 10 to facilitate the sliding movement of the signalling arm with respect to the block 8 and the stationary pintle 7 on which said block is mounted. This construction also enables the signalling arm and the block 8 to rotate simultaneously on the pintle 7 as will be hereinafter more fully set forth.

An internal gear designated generally by the numeral 18 and being of the same configuration as the base 10 of each signalling arm is secured on the bottom of the base. The bottom of the base is further provided with a groove or channel 19, which is also of the same configuration as the base and the internal gear 18, and this groove is disposed between the longitudinally extending slot 16 formed in the base, and the edges of the gear teeth 20 of the internal gear 18.

Extending upwardly through each of the supporting standards 6 is the rotatable drive shaft 21, the lower end thereof extending downwardly below the surface of the ground and being associated with an electric motor of any conventional construction, in any suitable manner. The upper end of the drive shaft extends through the platform 5 in a suitable opening 22 provided therefor.

Secured on the portion of the drive shaft which extends above the platform 5 is the pinion 23, the same being adapted for cooperation with the gear teeth 20 of the internal gear member 18. A spacing collar or washer 24 is also arranged on the upper portion of the drive shaft, and is disposed between the pinion 23 and the platform 5 in the manner as more clearly illustrated in Figure 5 of the drawings. A guide roller 25 is secured on the uppermost end of the drive shaft 21, and is adapted to travel in the groove or channel 19 formed in the bottom of the base 10. The spacing collars 9 or 24 will prevent the internal gear member 18 from coming in contact with the platform 5 and thus insure the spacing of the signalling member from the platform in order that the same will be free to slide and rotate during the operation of the signal.

An ornamental top piece 26 is adapted to be mounted on the top of each of the signal arms, and at the ends of the top member are supported any suitable visible signalling means such as shown at 27. The light rays from the lamps are arranged in each of the casings of the visible signalling means adapted to pass through one pair of adjacent sides so that a signal will be readily visible from either direction.

With reference now to Figure 1 of the drawings, it will be noted that the signalling members 1 and 2 are disposed transversely

into the street or highway on which traffic travels north and south, thus giving a signal for such traffic to come to a stop before reaching the intersection A.

In the mean time, the other pair of cooperating signal arms 3 and 4 are disposed parallel with the intersecting street or highway so that the traffic on this highway or street will be free to pass across the intersection in safety. This will also control the movement of 75 pedestrians.

The operation of my improved crossing signal may be briefly stated as follows. The signals are arranged in pairs and when one pair of these signals is disposed parallel to one highway, the other pair of signals will be disposed at right angles with respect to the intersecting highway, thus permitting the traffic to travel across the intersection in the direction desired when the signals for this 85 particular highway are parallel with the same.

The cycle of operation of each signal may be more clearly understood by defining the various points of the movable signal member with respect to the pinion and now considering Figure 4, it will be observed that the pinion 23 is located at point *b* of the internal gear 18 and when in this position, this particular signal member will be disposed at 90 right angles or ninety degrees with respect to the particular highway with which said signal is associated. While the switch 38 is closed, the electric motor will operate the drive shaft so that the pinion 23 will cooperate with the teeth 20 of the internal gear, and when the pinion is in engagement with the internal gear at the point C as shown in Figures 2 and 3, the signal will then be disposed parallel to the particular highway with 105 which the signal is associated, thus indicating that this highway is clear and that pedestrians and traffic moving along the same can proceed across the intersection without any danger.

When point *d* of the internal gear is in engagement with the pinion, the signal member will again have assumed a position at right angles to the highway with which said particular signal is associated. Finally when 115 point *a* of the internal gear is in engagement with the pinion, the signal will then be disposed parallel to its highway with which the same is associated.

It is readily obvious therefore that at each 120 quarter turn of the signal, the same is disposed at right angles with respect to the particular highway for which the signal is associated.

The signal may be stopped in any particular position by the traffic officer controlling the switch 28.

When the signalling means 27 is illuminated, the signal arms may be readily and easily visible for a suitable distance from the 130

street intersection, so that the drivers of vehicles quite some distance away from the intersection may readily ascertain the conditions of traffic at such points.

5 The provision of an internal gear member in the particular shape shown in the drawings will cause the signal arms to be disposed at an operative or inoperative position, and furthermore the block carrying the rollers will 10 cooperate with the tracks of the respective signal arms to permit the sliding movement of the latter, in order that the same may efficiently operate.

In Figure 6 of the drawings, the signalling 15 device is shown as being associated with a railway grade crossing, a pair of signalling arms being disposed on opposite sides of the track B, and being also arranged at the sides of the highway C, which intersects the tracks.

20 A crossing signal of the above mentioned character may be readily and easily set up in position for use and will at all times be positive and efficient in its operation to indicate the position at the intersection of one highway 25 way with another, as well as the intersection of railroad tracks with a road.

While I have shown the preferred embodiment of the invention, it is to be understood that minor changes in the size, shape, and arrangement of parts may be resorted to without departing from the spirit and scope of the appended claims.

Having thus described the invention, what I claim as new is:

35 1. A crossing signal comprising a support, a pintle extending upwardly from the support, a guide block mounted on the pintle and adapted for rotation thereon, a signal arm, said guide block extending upwardly 40 through the arm, cooperating means between the block and the arm to effect the sliding movement of the arm with respect to the block, means for rotating the signal arm on the support whereby the same is moved to an 45 operative or inoperative position, said last mentioned means comprising an internal gear carried by the bottom of the signal arm, a rotatable shaft extending upwardly through the support, and a drive pinion on the upper end of the shaft cooperating with the internal gear.

50 2. A crossing signal comprising a support, a pintle extending upwardly from the support, a guide block mounted on the pintle and adapted for rotation thereon, a signal arm including a base, upstanding end members, and side members arranged in spaced opposed pairs, the bottom of the base of the signal arm being provided with a longitudinally 55 extending slot, said guide block extending between the spaced sides of the signal arm, rollers associated with the guide block and engaging with the side members of the signal arm whereby said signal arm is adapted 60 for slidable movement with respect to the 65

guide block, and means for rotating the guide block and the signal arm to move the latter to an operative or inoperative position.

3. A crossing signal comprising a support, a pintle extending upwardly from the support, 70 a guide block mounted on the pintle and adapted for rotation thereon, a signal arm including a base, upstanding end members, and side members arranged in spaced opposed pairs, the bottom of the base of the signal arm being provided with a longitudinally 75 extending slot, said guide block extending between the spaced sides of the signal arm, rollers associated with the guide block and engaging with the side members of the signal arm whereby said signal arm is adapted for slidable movement with respect to the guide block, means for rotating the guide block and the signal arm to move the latter to an operative or inoperative position, said last 80 mentioned means comprising an internal gear secured on the bottom of the base of the signal arm, a rotatable shaft extending upwardly through the support, and a drive pinion mounted on the upper end of the shaft 85 and cooperating with the internal gear.

4. A crossing signal comprising a support, a pintle extending upwardly from the support, a guide block mounted on the pintle and adapted for rotation thereon, a signal arm including a base, upstanding end members, and side members arranged in spaced opposed pairs, the bottom of the base of the signal arm being provided with a longitudinally 90 extending slot, said guide block extending between the spaced sides of the signal arm, rollers associated with the guide block, and engaging with the side members of the signal arm whereby said signal arm is adapted for slidable movement with respect to the 95 guide block, means for rotating the guide block and the signal arm to move the latter to an operative or inoperative position, said last mentioned means comprising an internal gear secured on the bottom of the base of the signal arm, a rotatable shaft extending upwardly through the support, and a drive pinion mounted on the upper end of the shaft 100 and cooperating with the internal gear, and cooperating means between the upper end 105 of the shaft and the base of the signal arm to prevent the displacement of the pinion from the internal gear.

5. A crossing signal comprising a support, a pintle extending upwardly from the support, a guide block mounted on the pintle and adapted for rotation thereon, a signal arm including a base, upstanding end members, and side members arranged in spaced opposed pairs, the bottom of the base of the signal arm being provided with a longitudinally 110 extending slot, said guide block extending between the spaced sides of the signal arm, rollers associated with the guide block and engaging with the side members of the signal arm whereby said signal arm is adapted 115 for slidable movement with respect to the 120 guide block, means for rotating the guide block and the signal arm to move the latter to an operative or inoperative position, said last mentioned means comprising an internal gear secured on the bottom of the base of the signal arm, a rotatable shaft extending upwardly through the support, and a drive pinion mounted on the upper end of the shaft 125 and cooperating with the internal gear, and engaging with the side members of the 130

signal arm whereby said signal arm is adapted for slideable movement with respect to the guide block, means for rotating the guide block and the signal arm to move the latter 5 to an operative or inoperative position, said last mentioned means comprising an internal gear secured on the bottom of the base of the signal arm, a rotatable shaft extending upwardly through the support, a drive pinion 10 mounted on the upper end of the shaft and cooperating with the internal gear, cooperat-

ing means between the upper end of the shaft and the base of the signal arm to prevent the displacement of the pinion from the internal gear, said last mentioned means comprising the guide roller secured on the uppermost end of the drive shaft, the bottom of the base of the signal arm being provided with a groove in which said last mentioned roller is adapted to travel. 15

In testimony whereof I affix my signature. 20
JOHN A. RHOADES.
